PROCESS OF REFINING HYDROCARBONS

Earl Manning, Jr., Houston, Tex., assignor to
 Shell Development Company, San Francisco,
 Calif., a corporation of Delaware

No Drawing. Application June 13, 1947,
 Serial No. 754,597

10 Claims. (Cl. 196—39)

1

This invention relates to a process of refining paraffinic hydrocarbon compositions. More particularly, the invention is directed to a refining operation designed to increase the normal paraffinic hydrocarbon content of a hydrocarbon fraction which initially contains normal paraffinic hydrocarbons and other types of hydrocarbons, either or both aromatic and non-aromatic.

Various hydrocarbon mixtures may be obtained by the usual oil refinery operations. These mixtures usually contain normal paraffinic hydrocarbons in admixture with other types of hydrocarbons, such as iso-paraffinic hydrocarbons, cycloparaffinic hydrocarbons, e. g. naphthenes, and aromatic hydrocarbons. Such is the case of those hydrocarbon fractions having selected boiling ranges, dividing them into fractions, such as the very volatile and easily liquefied butanes, and pentanes, the gasoline hydrocarbons, the gas oil fractions, kerosene, the heavier fuel oils, the lubricating oil fractions, etc. Various chemical and physical processing operations have been utilized in the preparation of these mixtures depending on the uses to which they were to be put and the relationships between the different hydrocarbon types, and even the individual molecular species, and the required characteristics for the intended use. Thus, sulfuric acid treatment has been used to remove olefins and other acid polymerizable substances from gasoline fractions; a mixture of sulfuric acid and phosphoric acid has been proposed in U. S. 2,088,406 for removing olefinic constituents without at the same time removing desirable unsaturated aromatic compounds in the preparation of electrical insulating oils; fuming sulfuric acid has been used for removing aromatic and naphthenic hydrocarbons from oils to be used as transformer oil and lubricating oils; azeotropic and extractive distillation have been used to separate relatively close boiling hydrocarbons of different degrees of unsaturation one from the other(s) such as aromatics from non-aromatics, paraffinic from naphthenic, etc.

For many purposes, it is desirable to have available a hydrocarbon fraction with a high content or proportion of normal paraffinic hydrocarbons. Thus, for example, the quality of Diesel fuels as measured by the Diesel index or cetane number is a direct function of the n-paraffinic content. Normally solid, n-paraffin hydrocarbons are known to crystallize in a form different from the non-normal, i. e. iso- and cyclo-paraffinic hydrocarbons and for some purposes the form of the solid n-paraffin hydrocarbons is preferred.

2

Although the prior methods of refining and otherwise treating hydrocarbon mixtures are of value in improving on the value of the products thus produced for the intended use, they all possess certain disadvantages or are not applicable at all when the objective is to produce a composition with an increased content of normal paraffinic hydrocarbons, especially when it is desired to produce substantially pure n-paraffinic hydrocarbon compounds or mixtures consisting of n-paraffinic hydrocarbons with different numbers of carbon atoms per molecule.

It is, therefore, a principal object of this invention to provide an improved process for increasing the n-paraffinic hydrocarbon content of a hydrocarbon fraction containing initially both normal-paraffinic and other hydrocarbons, including non-normal paraffinic and aromatic hydrocarbons. A further object is to provide a process for improving the Diesel index or cetane number of a Diesel fuel. Another object is to provide a process for the separation of normal paraffinic from other hydrocarbons. Still another object of the present invention is to provide a process whereby normal-paraffinic hydrocarbons can be recovered as such, economically and in high yield, from admixtures thereof with iso-paraffins or cyclo-paraffins or aromatics, or mixtures thereof. These objects will be more clearly understood and other objects 30 will become evident from the description of the invention.

Now, in accordance with this invention, it has been found that normal chain paraffinic hydrocarbons may be effectively separated from other types of hydrocarbons, in mixtures thereof, by a chemical process, which process comprises treating the admixture of hydrocarbons with a chemical acid treating agent consisting essentially of a mixture of sulfuric and phosphoric acids, which 40 mixture is free of uncombined water and which acid mixture contains additionally an amount of inorganic acid anhydride which is in substantial excess of that which is required to convert all water, actual or hypothetical, present in the mixture into the normal water-stable acid of said acid anhydride.

Generally described the process of this invention comprises treating a hydrocarbon admixture of normal paraffinic hydrocarbons and other 50 types of hydrocarbons with a liquid chemical treating agent which is a chemical equilibrium system corresponding to a combination of sulfuric acid anhydride (sulfur trioxide), phosphoric acid anhydride (phosphorus pentoxide) and water in proportions such that, assuming the

water reacts with the acid anhydrides according to the equations:

and

then there is a substantial excess of inorganic acid anhydride, either or both sulfur trioxide or phosphorus pentoxide, over the equivalent amount of water as indicated by the above reactions, and removing reacted material and treating agent from the unreacted normal paraffinic hydrocarbons. Expressed another way, the total acid content of the treating agent, expressed as acid anhydride equivalent, is in substantial excess of the water equivalent thereof to form the water-stable acids from said acid anhydrides.

By treating a mixture of hydrocarbons, containing n-paraffinic hydrocarbons and other hydrocarbons with the treating agent in accordance with this invention, for example, with a mixture of concentrated sulfuric acid and phosphorus pentoxide, the other hydrocarbons are chemically modified and may be readily separated from the normal paraffinic hydrocarbons, which are not altered. Thus, by practicing this invention aromatic, cycloparaffinic and isoparaffinic hydrocarbons are separated from admixture with normal paraffinic hydrocarbons.

The liquid acid treating agents of this invention may vary considerably in actual composition and/or method of preparation. In fact, the molecular species actually present is largely a matter of conjecture. Nevertheless, regardless of the molecular species present in a mixture, for example, as made by dissolving one-third (1/3) of a gram-mol of phosphorus pentoxide in one gram-mol of hydrogen sulfate (100% sulfuric acid), the resulting treating agent is highly effective in removing non-normal paraffinic and aromatic hydrocarbons from admixtures with n-paraffinic hydrocarbons. Thus, the advantage is secured whether the treating agent is considered to contain uncombined phosphorus pentoxide dissolved in pure hydrogen sulfate; to contain uncombined sulfur trioxide in phosphoric and/or sulfuric acids; to contain pyrosulfuric acid in phosphoric acid; or to contain pyrophosphoric and/or metaphosphoric acids in sulfuric acid. In general, the acid treating agent should contain an amount of the inorganic acid anhydride as is equivalent at least to about 3.5% by weight of extra phosphorus pentoxide, or equivalent to a solution of substantially 100% sulfuric acid admixed with at least about 3.5% by weight of phosphorus pentoxide. Since H_2SO_4 and P_2O_5 have molecular or formula weights of 98 and 142, respectively, said above solution would correspond to approximately one mol of H_2SO_4 per 0.025 mol of P_2O_5 , or an amount of P_2O_5 which is equivalent to 0.075 mol of water to form H_3PO_4 . Proportions of acid anhydride as high as 30-40% by weight, based on the total acid content, may be utilized with advantage. It is preferred, however, to use acid treating agents which contain an amount of free acid anhydride of from about 5% by weight, or better about 5 mol per cent calculated as P_2O_5 , to about 15% by weight (about 20 mol per cent calculated as P_2O_5). Examples of suitable acid treating agents are (1) concentrated sulfuric acid (98.5% by weight pure H_2SO_4) containing 5 per cent by weight of phosphorus pentoxide, (2) concentrated (98-100%)

sulfuric acid containing 10 per cent by weight (based on the combined weights) of phosphorus pentoxide and (3) 80% by volume of fuming sulfuric acid (30% by weight excess SO_3) with 20% by volume of phosphoric (ortho) acid (85% H_3PO_4).

In practicing the invention, the ratio of the amount of the acid treating agent, as defined and discussed above and which may be represented for simplicity as $\text{H}_2\text{SO}_4\text{-P}_2\text{O}_5$ treating agent, to the amount of hydrocarbon mixture may be varied over a considerable range. A suitable range of ratios is from about 2:1 to about 20:1, by volume, a preferred ratio being from about 5:1 to about 15:1. Of course, higher ratios may be utilized, but, in general, it is not economically feasible or desirable to use a higher ratio than is required to obtain the desired results.

The process may be effected at various temperatures, and, in general, suitable temperatures are normal atmospheric temperature and moderately elevated temperatures. For treating a hydrocarbon mixture of the general fluidity and other characteristics of gasoline and kerosene fractions, satisfactory results are obtained by carrying out the process at normal room temperature, except insofar as the temperature of the mixture is increased by the heat of mixing and reaction. For such mixtures, a temperature of from about 10° C. to about 75° C. is preferred. With less reactive materials such as the lower molecular weight (4-5 C's) hydrocarbons, higher temperatures, may be utilized, e. g. up to about 100° C. In some cases, of course, the hydrocarbon mixture may be treated in the gaseous state by the liquid acid treating agent.

It will be understood that the various variable factors such as the ratio of acid treating agent to hydrocarbon mixture, temperature of treatment, manner of effecting contact between the treating agent and the hydrocarbon mixture such as by vigorous agitation in a tank or similar vessel or counter-current contacting in a contacting tower provided with suitable packing or other dispersing means, etc., amount of increase in n-paraffin content which it is desired to obtain in the product, ratio of n-paraffin hydrocarbons to other hydrocarbons in the mixture being treated, and the like, are inter-related and that consideration of these factors together will be necessary, as will be evident to one skilled in the art, for determining the optimum set of operating conditions for a given desired objective.

Although the process of the invention is suitable for treating any mixture of n-paraffin hydrocarbons together with other hydrocarbons for the purpose of enhancing the n-paraffin hydrocarbon content of the recoverable hydrocarbon product, the invention is of particular value for treating n-paraffin hydrocarbon concentrates which contain a major portion of normal paraffinic hydrocarbons, and particularly for the preparation of substantially pure n-paraffinic hydrocarbons from such concentrates.

Having set forth the general nature and objects of the invention, and having described in considerable detail the manner in which it is to be practiced, the invention will be more readily understood and its utility demonstrated by the following illustrative examples.

EXAMPLE I

Separate portions of a blend of pure hydrocarbons, the composition of which is given in Table I, were subjected to various acid treatments

with a ratio of acid to hydrocarbon blend of 10:1, and at room temperature, except insofar as the temperature was increased by the heat of the reaction. The acid and hydrocarbon blend were stirred vigorously throughout the reaction period. After the treatment was terminated the unreacted hydrocarbon fraction was separated from the acid phase. The separated hydrocarbon fraction was washed with alkali and water and dried. The pertinent data are tabulated in Table II.

TABLE I
Composition of hydrocarbon blend

Hydrocarbon	Vol. Per Cent
Normal octane	86.4
Dimethylcyclohexanes	3.6
Toluene	5.0
2,2,4-trimethylpentane	5.0
	100.0

TABLE II
Acid treatment of hydrocarbon blend

Description of acid	Treat- ment Time	Recovery, Per Cent of total vol. charged	Density $D_{4^{\circ}}$	Refractive Index $N_{4^{\circ}}$
Fuming H_2SO_4 (30%)	4 min.	51		1.39747
10% H_2SO_4	16 hrs.	64	0.7029	1.39750
98.5% H_2SO_4	do	85		1.39765
85% v. of 98.5% H_2SO_4	do	91	0.7045	1.39765
15% v. of 85% H_3PO_4				
98.5% H_2SO_4	do	78	0.7029	1.39750
20 g. PaO_4 per 100 ml. acid	do			
98.5% H_2SO_4	do	82	0.7027	1.39750
10 g. PaO_4 per 100 ml. acid	do			
80% v. fuming H_2SO_4 (30%)	4 hrs.	77	0.7028	1.39750
20% v. of 85% H_3PO_4			0.70260	1.39745
Bur. of Standards pure normal octane.				

Thus it is seen from the results in Table II, that treatments 1, 2, 5, 6 and 7 give substantially pure normal octane. However, it is to be noted that treatment 1, which was for the very short period of four minutes, gave only a 51% volume recovery against a theoretical recovery of 86.4% by volume. Also, it will be noted that treatment 2 required an extended period of time to remove the non-normal paraffinic hydrocarbons, as evidenced by the refractive index, and that with this required extended time of treatment the recovery was less than 75% of the theoretical. Treatments 3 and 4 gave good recovery, but the recovered product contained substantial proportions of non-normal paraffinic hydrocarbons. Treatments 5, 6 and 7, in which cases the acid treating agents were in accordance with the invention, gave good products, i. e. substantially pure normal octane and at the same time the recovery was about 90% by volume or better. It is observed that treatment 4, which is in accordance with the teaching of the above referred to U. S. Patent No. 2,088,406 is entirely unsatisfactory for the present purpose. In fact, the results appear to substantiate the teaching of said patent that a mixture of concentrated sulfuric and phosphoric acids does not remove aromatic from n-paraffinic hydrocarbons.

EXAMPLE II

A n-octane concentrate containing about 7% by volume of naphthenic hydrocarbons was stirred at room temperature for 16 hours with 10 volumes (per volume of concentrate) of an

acid agent made by dissolving 33 grams of phosphorus pentoxide in 100 ml. of 98% sulfuric acid. The resulting recovered raffinate, after being washed with caustic solution and water was found to have an index of refraction ($N_{D^{\circ}}$) of 1.3974 as compared with 1.3975 for pure n-octane.

EXAMPLE III

A hydrocarbon mixture of 84% volume n-octane, 6% v. dimethylcyclohexanes, 5% v. toluene, and 5% v. 2,2,4-trimethylpentane was treated similarly to the n-octane concentrate of Example II. The properties of the recovered product were those of n-octane and the recovery of n-octane was 89% by volume of the n-octane present in the mixture treated. A noteworthy feature is that the reaction products were all absorbed in the acid phase and that a redistillation of the separated and washed raffinate gave no evidence of heavy residual material.

EXAMPLE IV

The treatment of Example II was applied to a

Diesel reference fuel, and it was found that the Diesel index was increased from 77 to 91, although by a more severe treatment according to the 45 process of this invention it is possible to obtain a fuel having a still higher cetane value.

I claim as my invention:

1. A process of refining a hydrocarbon mixture containing normal paraffinic hydrocarbons and other hydrocarbons, which process comprises treating said hydrocarbon mixture with an anhydrous mixture of sulfuric and phosphoric acids as obtained by mixing concentrated sulfuric acid with from about 5% to about 30% by weight of 50 phosphorus pentoxide for a period of time whereby substantially all of said other hydrocarbons are reacted with and dissolved in said acid treating agent, thereby forming a hydrocarbon phase which is enriched in normal paraffinic hydrocarbons and an acid phase which contains a substantial proportion of said other hydrocarbons, and separating said phases.

2. A process of refining a normally liquid hydrocarbon mixture containing normal paraffinic hydrocarbons and other hydrocarbons, which process comprises treating each volume of said hydrocarbon mixture with from about 2 to about 20 volumes of an anhydrous mixture of sulfuric and phosphoric acids as obtained by mixing concentrated sulfuric acid with from about 5% to about 30% by weight of phosphorus pentoxide, said treatment being carried out at a temperature of from about 10° C. to about 100° C., thereby forming a hydrocarbon phase which is substantially enriched in normal paraffinic hydrocarbons

and an acid phase which contains a substantial proportion of said other hydrocarbons, and separating said phases.

3. A process of refining a hydrocarbon concentrate of a normal paraffinic hydrocarbon admixed with other hydrocarbons, which process comprises treating said hydrocarbon concentrate with an anhydrous mixture of sulfuric and phosphoric acids as obtained by mixing concentrated sulfuric acid with a substantial proportion of phosphorus pentoxide, said treatment being carried out at a volume ratio of said treating agent to said concentrate and for a period of time whereby substantially all of said other hydrocarbons are reacted with and dissolved in said acid treating agent and substantially all of said normal paraffinic hydrocarbon is unaltered, thereby forming a hydrocarbon phase of said normal paraffinic hydrocarbon and an acid phase containing said other hydrocarbons, and separating said phases.

4. A process of refining a normally liquid hydrocarbon concentrate of a normal paraffinic hydrocarbon admixed with other hydrocarbons, which process comprises treating each volume of said hydrocarbon concentrate with from about five to about fifteen volumes of an anhydrous mixture of sulfuric and phosphoric acids as obtained by mixing concentrated sulfuric acid with a substantial proportion of phosphorus pentoxide, said treatment being carried out at a temperature of from about 10° C. to about 75° C., thereby forming a hydrocarbon phase which is substantially pure normal paraffinic hydrocarbon and an acid phase containing said other hydrocarbons, and separating said phases.

5. A process of improving the cetane number of a Diesel fuel type hydrocarbon mixture which comprises treating said hydrocarbon mixture with an anhydrous mixture of sulfuric and phosphoric acids as obtained by mixing concentrated sulfuric acid with a substantial proportion of phosphorus pentoxide, thereby forming a hydrocarbon phase having an enhanced cetane number and an acid phase containing reacted hydrocarbons and unreacted acid, and separating said phases.

6. A process of improving the cetane number of a Diesel fuel type hydrocarbon mixture which comprises treating each volume of said hydrocarbon mixture with from about 2 to about 20 volumes of an anhydrous mixture of sulfuric and phosphoric acids as obtained by mixing concentrated sulfuric acid with from about 5% to about 30% by weight of phosphorus pentoxide, said treatment being carried out at a temperature of from about 10° C. to about 75° C., thereby forming a hydrocarbon phase having an enhanced cetane number and an acid phase containing reacted hydrocarbons and unreacted acid, and separating said phases.

7. A process of refining a liquid hydrocarbon concentrate of normal octane in admixture with other hydrocarbons which are not straight-chain hydrocarbons, which process comprises treating said admixture with an anhydrous mixture of

sulfuric and phosphoric acids as obtained by mixing concentrated sulfuric acid with a substantial proportion of phosphorus pentoxide for a period of time whereby substantially all of said other hydrocarbons are reacted with and dissolved in said acid treating agent, thereby forming an acid phase which contains substantially all of said other hydrocarbons and a hydrocarbon phase which contains said normal octane and is substantially free from said other hydrocarbons, and separating said phases.

8. A process for removing aromatic hydrocarbons, saturated alicyclic hydrocarbons and saturated non-straight-chain acyclic hydrocarbons from normal paraffinic hydrocarbons in admixtures thereof, which process comprises treating said admixtures with an anhydrous mixture of sulfuric and phosphoric acids as obtained by mixing concentrated sulfuric acid with from about 5% to about 30% by weight of phosphorus pentoxide, to thereby form a hydrocarbon phase which is substantially enriched in normal paraffinic hydrocarbons and an acid phase which contains a substantial proportion of the other hydrocarbons, and separating said phases.

9. A process for removing aromatic hydrocarbons, saturated alicyclic hydrocarbons and saturated non-straight-chain acyclic hydrocarbons from normal paraffinic hydrocarbons in admixtures thereof, which process comprises treating said admixtures with an anhydrous sulfuric acid-phosphoric acid treating agent prepared by mixing concentrated sulfuric acid with from about 5% to about 30% by weight of phosphorus pentoxide, to thereby form a hydrocarbon phase which is substantially only normal paraffinic hydrocarbons and an acid phase which contains a substantial proportion of the other hydrocarbons, and separating said phases.

10. A process of refining a petroleum hydrocarbon mixture containing normal paraffinic hydrocarbons and other hydrocarbons, which process comprises treating said petroleum hydrocarbon mixture with an anhydrous mixture of sulfuric and phosphoric acids as obtained by mixing concentrated sulfuric acid with a substantial portion of phosphorus pentoxide, for a period of time sufficient to produce a hydrocarbon phase which is substantially enriched in normal paraffinic hydrocarbons and an acid phase which contains at least a portion of said other hydrocarbons and producing said hydrocarbon and acid phases and separating said phases.
